(57) **CLAIM**

The ornamental design for a vehicle trailer, as shown and described.

DESCRIPTION

FIG. 1 is a rear right view of a vehicle trailer, showing my new design;

FIG. 2 is a front left view thereof;

FIG. 3 is a bottom plan view thereof;

FIG. 4 is a side elevation view with the opposite side being a mirror image thereof; and,

FIG. 5 is a top plan view thereof.

The broken lines illustrate portions of the vehicle trailer that form no part of the claimed design.
